(57) **CLAIM**

The ornamental design for a particle analyzer, as shown and described.

DESCRIPTION

FIG. 1 is a perspective view of the particle analyzer showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a left front perspective view thereof;

FIG. 9 is a left front perspective view thereof; and,

FIG. 10 is a left back perspective view thereof.

The broken line shows environmental structure of the particle analyzer and forms no part of the claimed design. The article is shown with a symbolic break in its width. The appearance of any portion of the article between the break lines forms no part of the claimed design.
